UNITED STATES PATENT OFFICE.

RAYMOND B. MEYER AND LEO C. YOUNG, OF WASHINGTON, DISTRICT OF COLUMBIA,
ASSIGNORS TO WIRED RADIO, INC., OF NEW YORK, N. Y., A CORPORATION OF
DELAWARE.

SIGNAL-TRANSMISSION SYSTEM.

Application filed December 15, 1926. Serial No. 155,072.

Our invention relates broadly to electron tube transmitters and more particularly to a circuit arrangement for a high frequency signal transmitter.

5 One of the objects of our invention is to provide a circuit arrangement for an electron tube transmitter which operates at relatively high frequencies under piezo electric crystal control with means for maintaining 10 the electron tubes in a condition of maximum operating efficiency at all times.

Another object of our invention is to provide a novel circuit arrangement for keying a high frequency signal transmission apparatus by which the grid electrodes of the tubes are prevented from becoming charged 15 at positive polarity for any protracted period thereby preserving the life of the tubes.

Another object of our invention is to provide 20 a bi-later circuit arrangement for the electron tubes of a high frequency signal transmitter whereby the tubes may be operated from a power source of alternating current for the transmission of high frequency 25 signals.

Another object of our invention is to provide 30 a crystal controlled high frequency signal transmission system in which the crystal controlled oscillator is maintained in a condition of continuous oscillation while the signals are effected by a change in condition 35 in the power amplifier circuit.

Still another object of our invention is to provide 40 a balanced circuit for a high frequency piezo electric crystal control transmission system the circuits of which are supplied with power from an alternating current source and in which the principle of frequency multiplying is employed with a 45 special circuit arrangement for obtaining the required high grid potential and the additional negative grid potential for blocking the operation of the frequency multiplying tubes in the production of signals.

50 Our invention will be more clearly understood from the specification hereinafter following by reference to the accompanying drawing which diagrammatically shows the circuit arrangement for the electron tube transmission system of our invention.

Our invention is directed to a piezo electric crystal controlled electron tube transmitter which may be operated from a single source of alternating current the frequency

of which may vary over a wide range such 55 as 25 to 1,000 cycles. The negative grid potentials for the operation of the electron tubes are obtained in a unique manner. The filament and plate potentials for the several electron tubes are obtained by the 60 interposition of transformers between the power source and the circuits of the electron tubes. The system of keying the electron tube transmitter is closely associated 65 with a method of producing the grid potentials for the several tubes. In the development of electron tubes transmitters we have endeavored to obtain negative grid potentials for the operation of the tubes from a 70 transformer so connected in the circuit that when the plate of any given tube has a positive potential impressed upon it the grid of the same tube is subjected to a negative potential. It follows that when the plate becomes negatively charged the grid has a 75 positive potential impressed thereon. In electron tube transmitters of piezo electric crystal control which employ the principle of frequency multiplying, the positive grid potentials are necessarily of a greater order 80 of magnitude than those ordinarily required while the negative potentials necessary to completely block the grid for keying purposes are also greater. In attempting to supply these potentials by means of a transformer it was found that after a short period 85 of operation the radio frequency output of the tubes materially decreased until a point was reached where oscillations ceased entirely. It was found that these tubes 90 could be restored to operation by burning the filaments brightly for a protracted period with no plate potential on the tubes. It was determined, therefore, that when the grids became highly positive the effect was 95 to temporarily destroy the electron emission of the tubes. The transformer method of supplying grid potentials, therefore, could not be used in sets of this type.

The circuit arrangement of our invention 100 was developed with a view of avoiding the detrimental effects of positive potentials on the grids. The circuit set forth in this application is so arranged that the grids are never subjected to positive potentials and 105 accordingly the continuous operation period of the tubes is prolonged. The negative potential is increased for the blocking of the

grids in the production of signals without undue arcing at the key contacts.

Referring to the drawing in more detail reference characters 1 and 2 designate the oscillator tubes, 3 and 4 indicate the frequency multiplier tubes and reference characters 5 and 6 show the power amplifier tubes. The antenna is represented at 7 and the counterpoise is shown at 8. The tubes are connected in balanced relationship throughout the several circuits as represented. The oscillator tubes 1 and 2 have their input circuits connected with the piezo electric crystal element 9 positioned between electrodes 10 and 11, the tubes 1 and 2 operating to sustain the oscillations of the piezo electric crystal element. The output circuits of the tubes 1 and 2 are coupled to the input circuits of the frequency multiplier tubes 15 through the coupling circuit 12. The output circuits of the frequency multiplying tubes 3 and 4 connect through coupling circuit 14 with the input circuits of the power amplifier tube system at 6. The energy at 20 increased amplitude is impressed on the antenna counterpoise system 7-8 through the coupling circuit 15. The filament transformer is designated at 16 as including primary winding 17 and secondary winding 18. The power supply line from the alternating current source is brought in at terminals 19 and after passing through main switch 20 is supplied to the primary windings of the several transformers. A circuit breaker 21 is interposed in the primary circuit for the protection of the system. A transformer 22 having secondary winding 23 and primary winding 24 supplies the plate potential for the oscillator tubes. The transformer 25 having secondary winding 26 and primary winding 27 supplies the plate circuits for the frequency multiplier tubes 3 and 4 and the power amplifier tubes 5 and 6. The primary windings 24, 27 and 17 are all supplied from the power source connected at 19. Connections are provided at 28 for measurements of the currents in various parts of the filament circuits.

We provide a resistance R_4 which is connected between the center or mid tap of the secondary winding 26 of transformer 25 and the key relay 29 from whence the circuit proceeds to the filament or ground through the ammeter A_5 . When the contacts of the key relay 29 are closed the plate circuits of the frequency multiplier and the amplifier tubes 3, 4, 5 and 6 are completed and plate current flows. This results in a drop of potential over R_4 . This resulting difference in potential is applied to the grids of the tubes 3 and 4 by means of the connections indicated by 30 and 31. It will be noted that the polarity of the potential applied to the grids is negative with respect to the filaments. By properly selecting the value of

R_4 the correct value of potential may be obtained for best operating characteristics.

R_3 is a resistance connected between the mid tap of secondary winding 23 of the plate transformer 22, supplying the potential for the master oscillator tubes 1 and 2, and filaments or ground. This arrangement produces the necessary negative grid potential for these tubes. It will be noted that this circuit is not keyed and therefore the tubes are permitted to oscillate continuously, a feature that is necessary, or at least, highly desirable when quartz crystal control is employed.

The contacts of key relay 29 are controlled by winding 32 through a control line 33. When the key contacts are closed, the frequency multiplier and amplifier tubes 3, 4, 5 and 6 receive plate current and the proper grid potentials are automatically established. Now, as the key contacts 29 are released the action is such that resistance, in the form of key contact resistance is inserted in the lead that connects the center of transformer secondary 26 to ground or filaments. Key 29 when open effects the opening of circuit 26-29-12. With this increase in resistance the potential drop becomes greater resulting in a greater negative potential being impressed upon the grids. This negative potential or rather the increase of resistance in turn reduces the flow of plate current and by the time the key contacts 29 are actually open, the negative potential on the grids has reached such a magnitude that the grid blocks and plate current ceases to flow. This prevents arcing at the key contacts and results in efficient and clean cut key action. When the key contacts are actually separated the resistance in the center lead is practically infinite and the negative potential (static potential) impressed on the grids equals in magnitude the voltage developed in the secondary of the plate transformer 25 between the center tap of winding 26 and the extreme end. The current which flows in the center tap is uni-directional pulsating current and thus the grids are never subjected to positive potentials as in the case where transformers are used to supply grid potentials. Another advantage of this system is that as plate current tends to increase, the drop over the resistance R_4 increases with a resulting increase in the negative potential applied to the grids which in turn automatically regulates the plate current. Hence it will be seen that there is established an automatic compensating action for limiting plate current to desired values.

A line relay 34 is provided for the control of the operation of the transformers through a power switch indicated at 35.

Our system of keying and the supplying of negative grid potential to the power am-

plifier tubes has proven highly satisfactory in operation, and although we have described the invention in a preferred embodiment we desire it to be understood that modifications may be made and equivalents employed without departing from the spirit of our invention.

What we claim as new and desire to secure by Letters Patent of the United States

10 is as follows:

1. A high frequency signal transmitter comprising a plurality of electron tubes each having grid, filament and plate electrodes, said tubes being connected for the generation of oscillations, the multiplication of the frequency of said oscillations and the increase in amplitude of the oscillations at multiplied frequency, a power source of alternating current, a transformer having primary and secondary windings with the primary winding thereof connected to said source and the secondary winding thereof arranged to impress high potential upon the plate circuits of said frequency multiplying tubes, a connection between a mid-point on said secondary winding to the filament electrodes of said frequency multiplying tubes, a high resistance interposed in said connection, a contact device located in series with said high resistance, a connection between the mid-point of said secondary winding and the grid electrodes of said frequency multiplying tubes for establishing a negative potential on the grid electrodes of said frequency multiplying tubes, said negative potential increasing upon the opening of said contact device.
2. A high frequency transmitter comprising a plurality of electron tubes each having grid, filament and plate electrodes said tubes being arranged in pairs and connected in balanced relation, one pair of said tubes being arranged for the generation of high frequency oscillations and another pair of said tubes being arranged to multiply the frequency of said oscillations while still another pair of said tubes is arranged for increasing the amplitude of said oscillations at multiplied frequency, an alternating current power source, a transformer including primary and secondary windings with the primary winding thereof connected with said power source and the secondary winding thereof arranged to supply plate potential to said frequency multiplying tubes, a mid-tap connection for said secondary winding and a pair of circuits extending from said mid-tap connection, one of said circuits connecting to the grid electrodes of said frequency multiplying tubes and the other of said circuits being connected with the filament electrodes of said frequency multiplying tubes, said last mentioned circuit including a resistance and a set of contacts in series therewith whereby the grid ele-

trodes of said frequency multiplying tubes may be normally subjected to a high negative potential and the negative potential decreased for the production of signals.

3. A high frequency signal transmission system comprising a plurality of electron tubes each having grid, filament and plate electrodes said tubes being arranged in pairs, one pair of said tubes operating to generate high frequency oscillations, another pair of said tubes operating to multiply the frequency of the oscillations generated by said first mentioned pair of electron tubes, and an additional pair of electron tubes operating to increase the amplitude of said oscillations at multiplied frequency, a power source of alternating current, a transformer having primary and secondary windings with the primary winding thereof connected with said source and the secondary winding arranged to supply plate potential for the circuits of said frequency multiplying tubes and said amplifying tubes, a mid-tap on said secondary winding, a connection between said mid-tap and the grid electrodes of said frequency multiplying tubes and said power amplifying tubes, a set of contacts interposed in said connection whereby a high negative potential may be normally impressed upon said grid electrodes and said negative potential decreased for the production of signals.

4. In an electron tube transmitter a circuit for generating high frequency oscillations, an electron tube frequency multiplier system connected with said circuit, an electron tube power amplifier system connected with said frequency multiplier system, grid, filament and plate electrodes for said electron tubes, a power source of alternating current, a transformer including primary and secondary windings said primary winding being connected with said source and said secondary winding having the mid-point thereof connected with the grid electrodes of said frequency multiplier and power amplifier tubes, a circuit including a high resistance and a set of contacts connected between said mid-tap and the filament electrodes of said frequency multiplier and power amplifier tubes, said grid electrodes being normally subjected to a high negative potential when said contacts are open, said contacts operating when closed to effectively include said resistance between said grid and filament electrodes decreasing the negative potential on said electrodes for the production of signals, the potential on said plate electrodes being automatically regulated in accordance with the voltage drop over said resistance.

In testimony whereof we affix our signatures.
